UNITED STATES PATENT OFFICE.

HERBERT B. TAYLOR, OF WESTFIELD, NEW JERSEY, ASSIGNOR TO WESTERN ELECTRIC COMPANY, INCORPORATED, OF NEW YORK, N. Y., A CORPORATION OF NEW YORK.

AUTOMATIC TELEPHONE SWITCH.

Application filed January 7, 1922. Serial No. 527,586.

To all whom it may concern:

Be it known that I, HERBERT B. TAYLOR, a citizen of the United States, residing at Westfield, in the county of Union, State of New Jersey, have invented certain new and useful Improvements in Automatic Telephone Switches, of which the following is a full, clear, concise, and exact description.

This invention relates to automatic switching apparatus, and more particularly to switches of the type adapted for use in automatic telephone exchange systems.

In the British Patent No. 183,438, issued to Western Electric Company, Limited, accepted September 6, 1923, an automatic telephone system is disclosed in which a switch structure is employed having certain rotatable bars each assigned to groups of incoming lines, other rotatable bars assigned individually to link conductors and still others to outgoing lines or trunks. Each of the incoming line bars being associated with a plurality of incoming lines is necessarily operable to participate in the establishment of coexisting connections between a plurality of its associated lines and idle trunks and by such an arrangement a very important economy is effected in that the number of operating bars and ancillary parts is materially reduced.

It has been found that successive operations of the line bars of the switch structure shown and described in the above noted British Patent No. 183,438 of 1923 sometimes tend to disturb existing connections sufficiently to produce noise on the subscribers' lines. This is due to the fact that a mechanical connection subsists between the operated contacts and the line bar.

The object of the present invention is therefore, the provision of a suitable switch structure of the character hereinbefore described which will obviate the possibility of successive operations of the line bars disturbing existing connections.

The principal feature of the invention consists in the combination with normally disengaged contacts of normally ineffective means for operating the contacts and other means operable to render the first means effective, the arrangement of such means permitting the second mentioned means to operate successively to participate in the estab-

lishment of coexisting connections without disturbing any of the connections previously established.

In its preferred form the invention consists in the combination with a contact set of a rotatable operating member and a pair of coordinate bars, one of which is operable to impart a preliminary movement to the operating member whereby the latter is rendered engageable by the other bar to be moved thereby into its fully operated position, in which position the operating member is unresponsive to further operations of the first bar.

Figs. 1 and 2 are both cross sectional plan views of the preferred form of the invention. Fig. 3 is a perspective view of the preferred form showing one contact set and the operating elements therefor. Fig. 4 is a fragmentary sectional elevation of the preferred form showing two sets of active contact wires and two sets of link conductors together with the operating members for the active contact wires. Fig. 5 is an isometric view of a modification of the selecting mechanism shown in Fig. 1. Figs. 6 and 7 are elevations of a modification.

In Fig. 1 there are shown, in cross section, two bars 1 of insulating material. These bars are usually of considerable length and embedded therein are a number of sets of horizontally extending active contact wires, each set in the present instance consisting of four wires 2, 3, 4 and 5. In the fragmentary view, Fig. 4, two such sets of active contact wires are shown. The active contact wires extend through the bars 1 and the rearwardly extending ends are used as soldering terminals for electrical connections. While only two of the bars 1 are shown in Fig. 1, in actual practice there would ordinarily be a considerable number of such bars employed, the number used being arbitrary and depending upon traffic requirements and economic considerations. The number of sets of active contact wires on each bar 1 is also arbitrary and likewise dependent on traffic requirements and economic considerations.

Extending horizontally and transversely of all the bars 1, are a number of sets of passive contact wires, each of which sets in

the present instance comprise four wires 6, 7, 8 and 9. These latter wires are supported at their ends and may also be supported intermediately of their ends by suitable supports not shown. The wires 6, 7, 8 and 9 are appropriately referred to hereinafter as link conductors. The link conductors taken in the aggregate together with their supporting members may be referred to as a grid on account of the grid-like appearance which they present when assembled.

As will be evident from the drawing, each set of link conductors is accessible to one set of active contact wires on each bar 1 and there would therefore be provided as many sets of link conductors as there are sets of active contact wires on a single bar 1. When the present switch structure is used in an automatic telephone system such as that described in the British Patent No. 183,438 of 1923 hereinbefore referred to, certain of the vertical rows of active contact sets comprising wires 2, 3, 4 and 5 are assigned to incoming lines and are divided into arbitrary groups, the sets of each group being multiply connected to an incoming line. It will, therefore, be seen that each incoming line has access to a plurality of sets of link conductors, but since there are a plurality of vertical rows of active contact wires assigned to incoming lines, it will also be seen that each set of link conductors is common to a plurality of incoming lines. The remaining vertical rows of active contact sets are each assigned to an outgoing trunk and the several sets of active contact wires comprising each such row are connected in multiple. It will accordingly be seen that each incoming line may have access to any trunk through the medium of any one of several sets of link conductors. To extend a connection from an incoming line an idle set of link conductors accessible to that line and an idle trunk are selected and two sets of active contact wires are operated to engage the selected set of link conductors.

In each vertical row of active contact sets assigned to outgoing trunks, only one connection may be had at a time as the entire row is connected to one trunk, but in the vertical rows assigned to incoming lines it is necessary that a plurality of coexisting connections may be established as each of these rows is divided into groups, each of which is connected to a different incoming line. It is, therefore, essential that the operation of establishing a connection in one of the latter vertical rows shall be accomplished without any disturbance of coexisting connections in that row. The mechanism for operating the active contact sets about to be described meets the above requirements.

With each set of active contacts there is individually associated a rotatable operable member comprising a metal yoke 10 embrac-

ing the non-rotatable bar 11 and having an integral rearwardly extending arm 10'. A coil spring 12 engages the bar 11 and yoke 10 and normally holds the yoke 10 in its non-operated position as shown in Fig. 3. To the yoke 10 there is attached a plate 13, preferably of insulating material, having four fingers 13', 13'', 13''' and 13''. Each of the active contact wires 2, 3, 4 and 5 is formed with a hump 2', 3', etc., with which the fingers 13', 13'', etc., are adapted to engage when operated and whereby the active contact wires are cammed into engagement with their associated link conductors 6, 7, 8 and 9.

For each vertical row there is a rotatable bar 14 provided with an armature 15 adapted to be attracted by an electromagnet 16 whereby the bar 14 is rotatable through a small angle. A plurality of fingers 17 one for each set of active contacts in the vertical row embrace the bar 14 and are yieldingly secured thereto through the medium of the coil springs 18. When bar 14 is rotated in response to an energization of its electromagnet 16, the fingers 17 thereon are moved into engagement with their associated plates 13 providing these plates are in their normal positions as shown in Fig. 3. By this operation of the fingers 17, the rotatable operating members comprising the yokes 10 and plates 13 are given a preliminary rotation against the tension of the springs 12 to a position wherein they may be individually selected and further operated by the longitudinally movable horizontal bars 19. The last mentioned bars are individual to the sets of link conductors and are provided with a plurality of laterally extending lugs 19', each of which is individual to one of the rotatable operating members, there being as many lugs 19' on each bar 19 as there are vertical rows of active contact sets. It will therefore be seen that each bar 19 is adapted to operate one set of active contacts in each vertical row. An electromagnet 20 and an armature 21 are provided for each bar 19 for operating the same and a restoring spring 22 is secured to the opposite end of each of said bars.

At the right-hand side of Fig. 1 an operating member is shown in its normal position. At the left-hand side of the same figure an operating member is shown in its preselected position to which it has been moved by the finger 17 wherein the arm 10' is so disposed as to be engageable by the lug 19' of the horizontal bar 19 upon a longitudinal movement thereof. The operating member at the right-hand side of Fig. 2 is shown operated and at the left of Fig. 2, the operating member is shown in its preselected position but in this instance the horizontal bar 19 was operated prior to the preliminary operation effected by the finger 17.

If the bar 19 of Fig. 2 should restore to normal while the operating member at the left of that figure is in the position shown, the lug 19' will pass the arm 10' by virtue 5 of the fact that both the operating member and the finger 17 are yieldingly mounted. Thus, the finger 17 may be pressed back against the tension of its spring 18 without turning bar 14, and consequently, without 10 disturbing any preselected operating member above or below in the same vertical row. In this connection it should be understood that all the non-operated operating members in the same vertical row are simultaneously 15 moved into their preselected positions in response to the operation of their associated bar 14.

When an operating member is fully operated as shown at the right of Fig. 2, further 20 operations of the bar 14 associated therewith are ineffective with respect to that operating member because the plate 13 is disposed out of reach of the finger 17 and coexisting connections are therefore not disturbed by the 25 operations of the bars 14 and the noise on the subscribers' lines which would otherwise be produced is obviated.

When the present switch structure is employed in the automatic telephone system 30 described in the aforementioned British patent, connections are established by selectively operating two of the vertical bars 14, one of which is associated with the calling incoming line and the other with an idle trunk, 35 and subsequently operating a bar 19 which is associated with an idle set of link conductors to which the incoming line has access.

As soon as a connection is established the 40 bar 14 associated with the incoming line is released and may be again operated to participate in the connection of another of its associated incoming lines with an idle trunk, and it may be repeatedly operated until all 45 of its associated incoming lines are connected to trunks providing there are enough trunks available.

In the modified form of Fig. 5 each set of active contact wires 2, 3, 4, and 5 is provided 50 with a card 23 of insulating material whereby the active contact wires are simultaneously moved into engagement with the link conductors 6, 7, 8 and 9. The horizontal bar 24 is rotatable by means of an electro- 55 magnet (not shown) and is provided with a plurality of laterally extending arms 25, one for each set of associated active contact wires. At the end of each arm 25 there is a pivotally mounted member 26 which is 60 normally held in the position shown by means of the spring 27. The vertical bar 28 is likewise rotatable and is provided with a plurality of hook-shaped pins 29 which when bar 28 is rotated out of its normal position are adapted to engage their associated

pivoted members 26 so as to turn them into such a position that their lower ends are in alignment with the V-shaped notches at the upper ends of the cards 23. When the members 26 have been thus preselected a rotary 70 movement of the bar 24 will cause the member 26 to engage the card 23 and to force the latter together with the active contact wires 2, 3, 4 and 5 downwardly into engagement with the link conductors 6, 7, 8 and 9. When 75 the contact set is operated the member 26 is positioned below and out of reach of the hook-shaped member so that subsequent operations thereof are ineffective to disturb coexisting connections. 80

The modified form of Figs. 6 and 7 is quite similar to that of Fig. 5. In this modification the laterally extending arms 30 are resilient in one direction. In Fig. 6 the arm 30 is shown in its normal position in full 85 lines and in its off-normal position in dotted lines. Upon a rotary movement of the vertical bar 31, the hook-shaped pins 32 thereon, press all the non-operated resilient arms 30 in their off-normal positions as indicated 90 by the dotted lines. After such preselecting operation a downward movement of the free end of an arm 30 effected by a rotary movement of the horizontal bar 33 will cause the arm 30 to engage the V-shaped notch on top 95 of the card 34 and to press the card together with the active contact wires downward into engagement with the link conductors. It is thought that the brief descriptions given in connection with Figs. 5, 6 and 7 will be sufficient for an understanding thereof in view of the extensive description herein of the preferred form of the invention as shown in Figs. 1 to 4, inclusive. 100

The invention is capable of modifications 105 and it is to be limited only by the scope of the claims hereinafter.

What is claimed is:

1. In a switch structure, a passive contact, an active contact, a member operable 110 to move said active contact with relation to said passive contact, means for effecting such operation of said member, said member being normally positioned out of engageable relation to said means and other 115 means operable to move said member into engageable relation with said first means, said member, when fully operated, being unresponsive to subsequent movements of said second means. 120

2. In a switch structure, a passive contact, an active contact normally disengaged from said passive contact, normally ineffective means for operating said active contact, and means for rendering the operation of said first means effective, said contacts when engaged, being unresponsive to subsequent operations of said second means. 125

3. In a switch structure, groups of contact sets, group selecting mechanisms each 130

individual to one of said groups of contact sets, operating means individual to one set of contacts in each group and effective to operate its associated sets in selected groups

5 but ineffective to operate its non-selected associated sets of contacts, said contacts being unresponsive to subsequent operations of said group selecting mechanisms.

4. In a switch structure, groups of contact sets, group selecting mechanisms each individual to one of said groups of contact sets, operating members individual to said sets of contacts, and operating mechanisms common to the several groups and each individual to one contact set in each group, means for moving said group selecting mechanisms to select their associated groups whereby said operating mechanisms are rendered effective with respect to the contact sets in the selected groups, the operations of said group selecting mechanisms being ineffective to transmit motion to operated contact sets.

5. In a switch structure, coordinate rows of contact sets, an operating member for each contact set, bars individual to the rows of contact sets in one direction, bars individual to the rows of contact sets in the other direction, the conjoint operation of one each of said bars being effective to positively operate one of said sets of contacts, the continued operation of said contact set being independent of one of said bars, and subsequent operations of said last mentioned bar being ineffective to transmit motion to the operated contact set.

6. In a switch structure, coordinate rows of contact sets, bars individual to the rows of contact sets in one direction, bars individual to the rows of contact sets in the other direction, each of said contact sets being selectively and positively operable by the conjoint operation of a particular bar of each set, the continued operation of any set of contacts being independent of the continued operation of one of the bars participating in the establishment thereof, said last mentioned bars being adapted to participate in the operation of other contact sets without transmitting motion to any of their associated previously operated contact sets continuing in operation.

7. In a switch structure, a contact set, an operating member for said contact set, a longitudinally movable bar for moving said operating member to operate said contact set, said operating member being normally positioned out of engageable relation with said longitudinally movable bar, and a rotatable bar adapted to transmit a preliminary movement to said operating member whereby the latter may be engaged by said longitudinally movable bar.

8. In a switch structure, a contact set, an operating member for said contact set,

a longitudinally movable bar for moving said operating member to operate said contact set, said operating member being normally positioned out of engageable relation with said longitudinally movable bar and a rotatable bar adapted to transmit a preliminary movement to said operating member whereby the latter may be engaged by said longitudinally movable bar, said operating member, when fully operated, being unaffected by any subsequent operations of said rotatable bar.

9. In a switch structure, passive contacts, active contacts normally disengaged from said passive contacts, a rotatable operating member for said active contacts, selective means for rotating said operating member to effect operation of said contacts, said operating member being normally unengageable by said selective means, and other selective means operable to effect a preliminary rotation of said operating member whereby the latter is rendered engageable by said first selective means.

10. In a switch structure, passive contacts, active contacts normally disengaged from said passive contacts, a rotatable operating member for said active contacts, a longitudinally movable bar for rotating said operating member to effect operation of said contacts, said operating member being normally unengageable by said bar, and a rotatable bar selectively operable to effect a preliminary movement of said operating member whereby the latter is rendered engageable by said first mentioned bar.

11. In a switch structure, passive contacts, active contacts normally disengaged from said passive contacts, a yieldingly mounted rotatable operating member for said active contacts, a restoring spring for said operating member, a longitudinally movable bar for rotating said operating member to effect operation of said contacts, said operating member being normally unengageable by said bar, a rotatable bar, a yieldingly mounted member on said bar, and a restoring spring connecting said last mentioned member with said rotatable bar, a rotary movement of said rotatable bar in one direction being effective to move the yieldingly mounted member thereon against said operating member when the latter is in its normal position and thereby to impart a preliminary movement to said operating member to render the latter engageable by said longitudinally movable bar.

12. In a switch structure, a contact set, a yieldingly mounted rotatable operating member for said contact set, a restoring spring for said operating member, a longitudinally movable bar, a lug on said bar for rotating said operating member to effect operation of said contacts, said operating member being normally unengageable by said lug, a

rotatable bar, and a yieldingly mounted finger on said bar, said finger being adapted to impart a preliminary movement to said operating member in response to rotation of said rotatable bar whereby said operating member is rendered engageable by said lug, said operating member when fully operated being disposed beyond the reach of said finger whereby subsequent operations of said finger are incapable of transmitting motion to said contact set.

13. In a switch structure, a contact set, an operating member for said contact set, an actuating bar for moving said operating member to operate said contact set, said operating member being normally positioned out of engageable relation with said actuating bar, and a second bar adapted to establish an engageable relation between said operating member and said actuating bar, said operating member when fully operated

being unaffected by any subsequent operations of said second bar.

14. In a switch structure, a row of contact sets, operating means common to said row, a plurality of other operating means each individual to one of said contact sets, said common operating means and one of said individual operating means being jointly operable to operate one of said sets, said individual operating means for maintaining the operation of said operated set while mechanically free from said common operating means whereby said common operating means is subsequently operable to assist in the operation of other contact sets without disturbing the contact set first operated.

In witness whereof, I hereunto subscribe my name this 3rd day of January, A. D. 1922.

HERBERT B. TAYLOR.
